UNITED STATES PATENT OFFICE.

HENRY G. VOIGHT, OF NEW HAVEN, CONNECTICUT, ASSIGNOR TO SARGENT & COMPANY, OF NEW HAVEN, CONNECTICUT, A CORPORATION OF CONNECTICUT.

MOLASSES-GATE LOCK.

1,377,531.

Specification of Letters Patent. Patented May 10, 1921.

Application filed August 18, 1919. Serial No. 318,358.

To all whom it may concern:

Be it known that I, HENRY G. VOIGHT, a citizen of the United States, residing in New Haven, county of New Haven, and 5 State of Connecticut, have invented certain new and useful Improvements in a Molasses-Gate Lock, of which the following is a full, clear, and exact description.

This invention relates to faucets, spigots, 10 etc., and more particularly to what are known in the trade as molasses or oil gates, in which a discharge spout or nozzle is provided with a swinging yoke or bail having a sliding valve plate or gate adapted to 15 close and open the discharge passage when the yoke is suitably actuated.

One object of my invention is to provide improved means for locking the valve controlling gate in its closed position by means 20 of a padlock so as to prevent theft of the liquid contents of the barrel or other receptacle in connection with which the gate is used.

Another object of my invention is to furnish a simple, efficient construction in which the padlock is located above and some distance from the discharge end of the gate or spout, so that there is no likelihood of 25 the liquid contents getting upon the padlock or the parts of the gate with which the padlock coöperates.

To these and other ends, the invention consists in the novel features and combinations of parts to be hereinafter described 30 and claimed.

In the accompanying drawing:

Figure 1 is a side elevation of a so-called molasses gate embodying my improvements, showing the gate locked in the closed position;

Fig. 2 is a top plan view of Fig. 1;

Fig. 3 is a side elevation similar to Fig. 1, showing the valve gate in its unlocked position, the spout being partly broken 45 away.

The gate selected for illustration has the usual spout or body portion 10 adapted to be mounted in a barrel, cask or other receptacle (not shown) in connection with which 50 the gate is to be used. A U-shaped yoke or bail 11 is pivoted or swiveled on the spout so as to swing vertically, the end portions of the U being swiveled to the wall of the body portion or spout 10 by means 55 of lugs or trunnions 12 projecting laterally

from the sides of the body portion 10. The intermediate portion 13 of the yoke 11 carries a sliding valve plate 14, preferably of brass, adapted to make a tight fit with the mouth portion 15 of the spout. The mouth portion 15 has a discharge opening 16 communicating with the hollow interior of the spout, and the mouth portion is curved on an arc concentric with the trunnions 12, the valve plate 14 being curved on a corresponding arc so as to slide over the discharge portion of the spout with a tight fit. When the yoke 11 is raised by the handle 17 into the position shown in Fig. 3, the opening 16 will be uncovered so that the 70 liquid can be drawn from the receptacle, but when the yoke is moved down again into the position shown in Fig. 1, the plate 14 covers the discharge opening so as to cut off the flow of liquid.

The body portion 10 and yoke 11 are preferably made of cast iron, the yoke being formed of two parts secured together by screws 18. Between the two parts of the yoke 11 is formed a socket, as shown more 80 particularly in Fig. 3, in which is mounted a coiled spring 19, the socket being formed partly in one yoke member and partly in the other. This spring 19 engages the outer face of the valve plate or gate 14 so as to 85 press it tightly against the curved end surface of the spout, which forms a seat for said plate, in order to prevent leakage. An outer projection 20 on the valve plate 14 extends into the coils of the spring so as to 90 maintain the parts in their proper relation.

The mechanism so far described is old, as shown in the H. B. Sargent Patent No. 1,199,501, granted September 26, 1916, and forms no part of my invention. My invention, which, as above stated, consists in providing improved means for locking the valve plate or gate 14 in its spout closing position, will now be described.

Upon one side of the spout or body portion 10, some distance from the discharge end of the same, is provided an upwardly extending projection 21, the same being preferably positioned directly above one of the lugs or trunnions 12. Upon one of the legs 105 of the U-shaped yoke 11 is formed a projection 22, the same being positioned to align with the projection 21 when the yoke 11 is moved to its spout closed position, drill holes 23 being formed through the projec- 110

tions 21 and 22 in alinement with each other and adapted to receive the shackle of a padlock 24.

From the construction just described it will be seen that the projections 21 and 22 not only form a very convenient means for locking the valve plate or gate 14 in its spout closing position, but that this arrangement retains the padlock 24 above the spout 10 at some distance from the valve closing end of the same, so that there is very little likelihood of the liquid which may be drawn out of the molasses gate becoming accidentally smeared over the padlock.

It will be apparent that various changes may be made in the device herein disclosed without departing from the scope of my invention as defined in the inclosed claims.

What I claim is:

1. In combination, a molasses gate or spout having a discharge opening, and a yoke swiveled thereon and carrying a valve to control said opening, said yoke having a padlock opening positioned upon the side of 25 swivel point opposite said valve, whereby said padlock opening moves downwardly when said valve is moved upwardly to uncover the discharge opening.

2. In combination, a molasses gate or spout having an opening, a yoke swiveled thereon and carrying a valve to control said opening a projection formed upon said gate or spout at said swivel point and extending therefrom in a direction away from 35 said valved opening, and means to lock said yoke to said projection when said valve is in spout closing position.

3. In combination with a molasses gate or spout having a discharge opening, a U-shaped yoke swiveled thereupon, and a valve carried by said yoke and movable thereby over said opening; means for locking said yoke in its spout closing position, comprising a projection upon said U-shaped 45 yoke adjacent said swivel, a coöperating

projection upon said gate or spout, said projections being on the side of said swivel opposite said valve and opening and having alined openings, and a padlock having a shackle extending through said alined openings.

4. In a locking device in combination, a molasses gate or spout having an opening, and a yoke swiveled thereon and carrying a valve to control said opening, said yoke having a padlock opening positioned above the spout body and substantially in vertical alinement with the swivel point when in locking position.

5. In a molasses gate or the like, a spout having a discharge opening, a U-shaped yoke having legs pivoted to said spout, a valve carried by said yoke and movable thereby over said discharge opening to close the same, one of the legs of the U-shaped yoke being extended beyond its pivot and means for locking said extended portion against movement relative to said spout.

6. In a molasses gate or the like, a spout having a discharge opening, a U-shaped yoke having legs pivoted to said spout, a valve carried by said yoke and movable thereby over said opening to close the same, one of the legs of said yoke being extended beyond its pivot, a projection on the spout 75 adjacent said extended end, and means to lock said end to said projection.

7. The combination of a spout having a discharge opening, a lever swiveled upon said spout, a valve carried by said lever and movable thereby over said discharge opening to close the same, said lever having an extension beyond the swiveled point of the same and remote from the valve, and means for locking said extension to said spout to 80 prevent movement thereof.

In witness whereof I have hereunto set my hand on this 15th day of August, 1919.

HENRY G. VOIGHT.
